HYDRAULIC IMPACT TOOL

William H. Cline, Jr., Houston, Tex., assignor to
 Hughes Tool Company, Houston, Tex., a cor-
 poration of Delaware

Application June 16, 1951, Serial No. 231,988

5 Claims. (Cl. 121—27)

1 This invention relates to impact or percussion tools and in particular to a tool of this type of utility in the drilling of earth bores for water, oil, gas, sulphur, and the like.

It is known in the rotary method of drilling earth bores to supplement the cutting action of conventional types of earth boring bits with impacts to facilitate the rate of disintegration of the bottom of the earth bore being formed. The impacts are usually effected by mechanisms actuated by the flushing fluid pumped downwardly through the drill pipe to the bit where such fluid serves to keep the drill cool and free from cuttings, and to thereafter rise in the well bore about the device and the drill pipe and remove the cuttings from the bore.

In the past, springs have been used for effecting actuation of the valving mechanism whereby the flushing fluid is intermittently supplied to the hammer assembly so that energy is alternately imparted to and delivered by such assembly. Inasmuch as devices of this type operate at hundreds of cycles per minute, difficulty is encountered from breakage of the valve actuating springs and from variations in the constants of such springs during normal use of the device whereby efficiency of the device is greatly impaired. It is therefore the primary object of the invention to provide an impact tool in which springs are eliminated from the valving mechanism.

Another object is to provide an impact tool having a valving mechanism operable by hydraulic pressure to produce desired valving action.

Another object is to provide, in one form of the invention, a valving mechanism which includes a valve sleeve which is moved hydraulically to a retracted position for the succeeding stroke as soon as the valve has opened.

A still further object is to provide a valving mechanism actuated to retracted position by the differential pressure between the interior and the exterior of the tool.

Still another object is to provide an impact tool in which an annular piston and a valve sleeve cooperating therewith provide an extensible valve mechanism which presents a large area for the exertion of pressure to initially accelerate the hammer in a downward direction and also to decelerate the hammer as it moves to its terminal upward position preliminary to downward acceleration thereof on the succeeding stroke.

Other objects and advantages of the invention will be more fully apparent from the following description, considered in connection with the accompanying drawings in which:

2 Fig. 1 is an elevational view of an impact tool embodying the invention, parts being shown in section to illustrate construction and operation of the device;

5 Figs. 2, 3, 4, 5 and 6 are sectional views taken respectively on lines 2—2, 3—3, 4—4, 5—5 and 6—6 of Fig. 1.

10 Figure 7 is a partial view similar to that of Figure 1, showing the piston and valve sleeve in their lower positions.

15 In the drawings an embodiment of the impact tool of the invention is shown generally at 1 attached to the lower end of a drill stem 2, a bit 3 being attached to the lower end of the tool.

20 To facilitate assembly and maintenance of the tool the housing 4 is made up of sections 5 and 6 interconnected by threads 7. The lower end of the housing includes a collar 8 to which is attached a drive bushing 9 having an upwardly extending shank 10 which serves as an anvil to receive impacts from the hammer thereabove. As is well known in the art, a splined connection is provided between the bushing 9 and the lower end of the section 6 of the housing 4 so that axial but nonrotative movement may be had between the bit 3 and the tool 1. It is to be understood of course that the hammer and anvil may be integrated in which case the impacts are applied directly by the bit 3 to the formation being drilled.

30 The valve mechanism is shown generally at 11 as comprising an annular piston 12 with axial passage 13. This piston is mounted for limited reciprocation in the upper end of the housing 4. The stop 14 in the housing serves to terminate downward movement of the piston and an upper stop, such as the end of the pin 15 on the end of the drill stem 2 serves to determine the upper limit of travel of the piston.

35 The lower end of the piston 12 is reduced at 16 to slidably and sealably fit within the valve sleeve 17 which in turn passes slidably and sealably through the inwardly extending flange 18 in the housing 4. Suitable stop means, such as the rib 19 on the valve sleeve 17, is engageable with the flange 18 to terminate downward movement of the valve sleeve relative to the housing 4. It seems apparent that the valve mechanism, just described, and its relationship with the housing

40 4 provides a chamber 22 above the flange 18 and about the valve sleeve 17, and such chamber is provided with passages 21 whereby fluid within the chamber is equalized with the pressure exteriorly of the housing 4.

45 The hammer 25 is reciprocable within the section 6 of the housing 4 and is guided in its path

of travel by upper and lower axially extending fins 26 and 27 of which the latter form a shoulder for the compression spring 28 having its upper end engaging shoulder 29 on the hammer whereby the hammer is constantly urged upwardly. Upward movement of the hammer under influence of the spring 28 moves the ball 30 into engagement with the seat 31 at the lower end of the valve sleeve 17 and hence normally holds the valve in engagement with its seat and the valve mechanism in its uppermost position when the tool is not in operation.

By way of further description of the invention and explanation of the operation of the disclosed embodiment, it will be assumed that the parts are in the relative positions shown in Fig. 1 of the drawings. The drill stem 2, the tool 1 and the bit 3 will be rotated in the usual manner. During such rotation, flushing fluid is pumped downwardly through the drill stem 2 where it exerts a pressure upon the upper end of the piston 12 and the ball valve 30, whereby the piston 12, the valve sleeve 17, the ball 30 and the hammer 25 will be accelerated downwardly. When the piston 12 engages stop 14 travel of the piston is terminated but the continuing flow of fluid to and through the passage 13 in the piston will cause the valve sleeve to travel until the rib 19 on the sleeve engages the flange 18 in the housing 4 whereupon travel of the sleeve is terminated. During the continued travel of the sleeve, energy transmitted by the pumped fluid continues to accelerate the hammer 25.

It is to be noted that the fluid pressure initiating the downward movement of the hammer is applied throughout an area equal to that of a circle having the outer diameter of the piston 12. Thus the energy of the pressure fluid is efficiently used to accelerate the hammer 25 which is further accelerated by the fluid entering the passage 13 after the piston has engaged the stop 14. This action continues until the rib 19 on the valve sleeve 17 engages the flange 18 in the housing 4 at which time the hammer has attained its maximum velocity.

At the instant the rib 19 of the valve sleeve 17 engages the flange 18 the ball valve 30 moves from its seat 31 and the fluid then flows unobstructedly about the hammer, through the passage 20 in the drive bushing and thence through the fluid passages in the bit 3 to rise about the tool and drill stem as already explained.

It is apparent that there is a drop in fluid pressure as the fluid passes downwardly to and through the bit 3. Hence, the fluid pressure within the tool is greater than the pressure on its exterior, a condition of importance in the operation of the tool.

When the ball 30 leaves its seat, as illustrated in Fig. 7, the valve sleeve 17 moves upwardly until it engages the nether side of the piston 12. This movement is brought about by the pressure within the tool upon an annular area of the sleeve having a cross section indicated as A₁. Such pressure is opposed by a pressure in the chamber 22 upon a like area on the upper end of the sleeve indicated as A₂. Since the pressure within the tool is greater than that on its exterior as already explained, the differential pressure in an upward direction causes the valve sleeve to move upwardly. At the same time the hammer 25 continues its downward travel and engages the shank or anvil 10 on the drive bushing to impart energy by impact to the bit to supplement cutting action thereby.

The hammer then moves upwardly and the ball 30 is again brought into engagement with its seat 31 on the valve sleeve 17. Pressure again builds up above the piston 12 and the ball 30 and such pressure decelerates the upward movement of the hammer. The valve sleeve 17 and the piston 12 move upwardly with the hammer until its velocity is reduced to zero whereupon the succeeding stroke is initiated.

Not only does the invention, described by reference to the embodiment shown in the drawings, obviate the use of springs to obtain desired valving action but the structure is also such that pressure fluid is applied to a piston of large cross section at those instants when a force of high magnitude is necessary to produce high acceleration of the hammer at the beginning of its downward stroke and to produce high deceleration of the hammer as it approaches the end of its upward stroke.

The invention provides an impact tool capable of attaining the objects above set forth and also a tool having high operating efficiency with a minimum of maintenance. While the description is directed to a specific embodiment it is understood that the construction and combination of the salient features of the invention may be altered without departing from the spirit of the invention.

30 The invention claimed is:

1. In a fluid actuated impact tool the combination comprising, a housing having a passage therethrough, there being spaced inlet and outlet for the admission and exhaust of actuating fluid to and from the housing, a reciprocable hammer within the housing intermediate the inlet and outlet, means for moving the hammer upwardly after an impact has been exerted thereby, a valve sleeve slidable axially of the housing and in sealing engagement therewith, said sleeve being engageable with the hammer to close the passage through the sleeve so that fluid pumped into the housing above the sleeve forces the sleeve and hammer downwardly, means for terminating the downward movement of the sleeve, whereby the seal between the sleeve and hammer is broken, means including an annular piston having a portion fitting telescopically within the sleeve so that the upper surface of the sleeve is isolated from fluid pressure applied to the interior of the sleeve, and additional means for subjecting said upper surface to the fluid pressure exteriorly of the housing so that the valve sleeve moves upwardly under differential pressures exerted thereon after said seal is broken.

2. In a fluid actuated impact tool the combination comprising, a housing having a passage therethrough, there being spaced inlet and outlet for the admission and exhaust of actuating fluid to and from the housing, a reciprocable hammer within the housing intermediate the inlet and outlet, means for moving the hammer upwardly after an impact has been exerted thereby, an annular piston mounted for reciprocation in the housing above the hammer, stop means in the housing for limiting the movement of said piston, within the housing, a valve sleeve telescopically surrounding said piston and adapted to engage and form a seal with the hammer, whereby the piston, sleeve and hammer move as a unit under pressure of fluid entering the housing above the piston, means for terminating downward movement of said sleeve after predetermined downward movement thereof relative to

the piston, and means for thereafter hydraulically lifting the sleeve relative to the piston.

3. In a fluid actuated impact tool the combination comprising, a housing having a passage therethrough, there being spaced inlet and outlet for the admission and exhaust of actuating fluid to and from the housing, a reciprocable hammer within the housing intermediate the inlet and outlet, means for moving the hammer upwardly after an impact has been exerted thereby, an annular piston mounted for reciprocation in the housing, a valve sleeve slidably and sealably surrounding said piston and engageable with the hammer to close the passage through the housing, and a seal between said sleeve and the housing below the piston, there being a passage between the interior and exterior of the housing above said seal whereby the sleeve is subjected to the differential pressure between the interior and exterior of the housing and moves to an upward position when the hammer moves from engagement with the sleeve.

4. In a fluid actuated impact tool, a tubular housing having spaced inlet and outlet for the admission and exhaust of the actuating fluid to and from the housing, an inwardly extending flange in the housing and spaced from the upper end thereof to form upper and lower chambers in the housing a valve sleeve slidably within said flange, an annular piston reciprocable in the upper chamber and having telescopic relation with said sleeve, whereby an annular chamber is formed about said sleeve, there being a port in

the housing between said annular chamber and the exterior of the housing, a hammer reciprocably mounted in the lower chamber, and means normally urging said hammer in an upward direction to engage and form a seal with said sleeve to close the passage through the tool.

5. In a fluid actuated impact tool, a tubular housing having spaced inlet and outlet for the admission and exhaust of the actuating fluid to and from the housing, a valve assembly reciprocably mounted therein, and comprising, an annular piston and a valve sleeve mounted for telescopic movement, separate means for limiting the downward travel of the piston and for thereafter terminating downward movement of the valve sleeve whereby the piston and sleeve are in extended position, a seal between the sleeve and housing whereby an annular chamber is formed about the valve assembly, there being a passage between said chamber and the exterior of the housing, a hammer reciprocably mounted in the housing below said valve assembly, a seat on said sleeve engageable by said hammer to close the passage through the tool, and means normally urging the hammer in an upward direction to engage said seat.
